CENTRIFUGAL BLOWER CONSTRUCTION

Kenneth Campbell, Ridgewood, N. J., assignor to
Wright Aeronautical Corporation, a corpora-
tion of New York

Application January 31, 1941, Serial No. 376,757

2 Claims. (Cl. 230—127)

This invention relates to centrifugal blowers and is particularly concerned with improvements in the construction of blowers which are adapted for very high speed operation along with large delivery and substantial pressure rise.

The provisions of the invention are particularly applicable to aircraft engine superchargers but the teachings of the invention may likewise be utilized in connection with centrifugal blowers in general. The desideratum in a supercharger is to deliver a large air volume at a pressure considerably in excess of atmospheric, and to do this with a blower impeller and diffuser of very compact size. Thus it is apparent that the impeller must rotate at very high speed and that air velocity through the impeller must be high. To get high pressure rise without an excessive velocity, the use of an impeller having backwardly sloping self diffusing vanes is indicated; the vanes should be wide for good blower capacity and for effective diffusion.

The impeller vanes according to this invention are carried by a curved hub member supporting the vanes only at one end in spaced parallel relation with the impeller axis to leave a clear axial air inflow opening. Since the curved vanes extend in an axial direction from the hub, their outer ends are supported by an integral shroud ring, which ring provides structure to resist centrifugal force and likewise provides a mask at the ends of the intervane passages to suppress turbulence of airflow through the passages. To be satisfactory structurally, the shroud must extend in a radial direction to prevent warping and failure from the action of centrifugal force.

With a large plurality of the sloping impeller vanes mentioned, the aspect ratio of the air passages is high; that is, the width of each passage is great as compared with its height. This is highly desirable to maintain a uniform velocity of air at all points in the cross section of the impeller passage. When the leading edges of the impeller vanes are substantially parallel to the impeller axis, as is herein contemplated, it is necessary to turn the air in as uniform a manner as possible from its axial inflow direction to a radial outflow direction, at the same time maintaining good distribution across the impeller vane entrance spaces. This I propose to accomplish by placing annular stationary turning vanes in the impeller eye, whose own aspect ratio as to the entering air, is high. These vanes pick up consecutive annular increments of entering air and discharge them radially outwardly, whence they blend into a radially flowing mass which is picked

up by the impeller vanes for delivery to the diffuser embracing the impeller. The vanes in particular serve to change the entering air direction so that it flows smoothly through the zone along the inner face of the impeller shroud, which would otherwise be full of turbulent, low pressure air due to the failure of incoming air to make the necessary sharp turn around the shroud inner edge.

Thus the several features of the structure herein disclosed combine to afford a supercharger assembly which is sound structurally and efficient aerodynamically.

In prior impellers and superchargers, two common faults included the turning of air through passages of low aspect ratio, and the breaking away of air from one face or shroud of the impeller due to too sharp a turn from the axial to the radial path, causing turbulent flow, poor velocity distribution, and curtailment in blower capacity and efficiency. These faults are wholly overcome in the present invention. It might here be mentioned that conventional supercharger impellers have utilized radial vanes and stationary shrouds. It has been realized that the integral rotating shroud has advantages in preventing slip of air from one impeller passage to the next, and in preventing the turbulizing effect due to air friction which occurs between the fast moving air and the stationary shroud. However, an integral shroud in the old type impeller would not be likely to secure all the advantages possible unless the air is properly turned from axial to radial flow to avoid separation of air from the shroud surface, to enable an even velocity distribution across impeller passages, as gained by the turning vanes of this invention. Thus, the turning vanes are applicable either to stationary or integral shroud impellers and it is believed that their use may increase the efficiency of supercharges of any type to which they are applicable.

To indicate the necessity of extreme refinement in supercharger design as herein taught, for an aircraft engine of 1,000 H. P., the impeller speed is of the order of 18,000 R. P. M.; the impeller diameter is of the order of 11 inches; the air mass moved at sea level is of the order of 1450 cu. ft./min., or 110 lbs. per min.; and the air velocity at the impeller outlet as it addresses the diffuser vanes is of the order of 1200 ft./sec. For high altitude, air mass moved increases to 125 lbs./min. and 3100 cu. ft./min. Some of the objects of the invention will be apparent from the foregoing.

An object of the invention is to provide stationary, annular guide vanes in a centrifugal blower rotor system which serve to alter the axial entering air to a radial path, the radial air flow leaving the guide vanes then being picked up by the blower vanes. Still another object is to provide an impeller construction having spiral vanes and having an integral shroud, i. e., integral side plates bordering the impeller blades for their mechanical support and for their greater aero-dynamic efficiency.

The invention is susceptible to various changes and modifications as will be pointed out in the detailed description below in connection with the drawing, in which:

Fig. 1 is a longitudinal section through one form of aircraft engine supercharger incorporating the teachings of the invention;

Fig. 2 is a section on the line 2—2 of Fig. 1; and

Figs. 3 and 4 are fragmentary longitudinal sections showing alternative constructions for the impeller and guide vanes.

All of the figures show the same essential impeller and diffuser construction, whereas Figs. 1, 3, and 4 show different arrangements of turning vanes for air flow entering the impeller. The first part of the description below applies to all of the figures, and the detailed differences in the turning vane provisions will be taken up thereafter.

A diffuser housing 10 comprises a portion of the general housing structure provided with bearings, not shown, in which an impeller shaft 11 is carried. To the shaft 11 an impeller 12 is keyed as at 13, the impeller comprising a hub 14 blending into a backplate 15 in clearance relation with a skirt 16 on the diffuser housing 10. The outer surface of the backplate 15 may be either plane or slightly dished while the inner surface of the backplate is preferably substantially plane, as at 18, blending in a smooth curve into the hub portion 14. Integral with the backplate 15 are a plurality of spirally-shaped blower vanes 20 whose inner entering edges 21 intersect the backplate 15 substantially at the juncture thereof with the hub 14 and extend nearly parallel to the impeller axis. The outer trailing edges 22 of the blower vanes 20 are also substantially parallel to the axis of rotation of the impeller. These vanes define inter-vane passages of relatively high aspect ratio for effective velocity distribution throughout cross sections of the passages. That is, the circumferential width of each passage is fairly small compared with the length of the leading edge of the vane. Integral with the righthand edges of the vanes 20 is a shroud element 23 whose inner surface 24 is substantially plane and whose outer surface is dished and runs in clearance relation with an inner skirt portion 26 of the diffuser 10. The innermost portion of the shroud 23 is formed as an enlarged bead as at 28 to provide a ring having great strength against bursting under the centrifugal loads imposed thereon by high speed impeller rotation. It will thus be seen that the shroud 23 and the impeller backplate 15 support themselves and the vanes 20 against centrifugal force. The impeller passages between the shroud and the backplate are substantially radial which is necessary to allow of economical distribution of impeller material against centrifugal stress.

The air intake to the impeller, commonly called the impeller eye, is defined between the impeller hub and the shroud inner border, and entering air must accordingly make a right-angled turn

from an axial direction of flow to a radial direction of flow. Under the high air velocity conditions encountered in high speed impeller operation, there is a tendency for the entering air to pile up against the backplate surface 18, endowing the impeller system with uneven pressure and velocity distribution across the impeller passages. To attain uniform pressure across the passage a plurality of annular turning vanes 28, 29 and 30 are carried by spokes 31 secured to a ring 32 attached to the diffuser housing 10. The several vanes 28, 29, and 30, in cross sectional profile, are concentric with one another and are substantially concentric with the impeller eye in its transition from axial to radial form, the turning vanes gradually increasing in chord or width toward the impeller axis. Likewise their leading edges are long compared with their relative spacing. It will be apparent that these turning vanes will guide the air toward a radial path in several strata, preventing high velocity near the surface 18 and low velocity near the surface 24. These vanes, being non-rotative, are not subject to the effect of centrifugal force.

In Fig. 3 a plurality of turning vanes 34 are shown, supported by spokes 35 on the diffuser housing. These turning vanes have a similar cross sectional profile and similar chord or width, but are progressively different in their overall diameter in order to traverse the distance across the impeller eye. The tendency of the vanes of Fig. 3 will be to hold entering air toward the inner face 24 of the shroud, preventing this air from being hurled due to its inertia, against the backplate face 18. The vanes 34, being of equal chord, will have substantially the same drag so as not to upset distribution of air flow to the rotating part of the impeller by drag differences.

In Fig. 4 a plurality of short chord turning vanes 38, 39 and 40 are shown, these annular vanes being supported by spokes 41 secured to the diffuser housing. The vane 38 is the innermost radially, and upstream from the others, while the vane 40 is outermost and is downstream of the others. The vanes have a turning effect on different annular strata of entering air, the downstream vanes also affecting that air leaving the upstream vanes. The echelon vane arrangement tends to prevent separation on the convex or cambered vane sides, and laminar flow without turbulence is thus maintained throughout the passage.

It will be appreciated that for any impeller design the turning vane arrangements may have to be changed and experimented with in order to secure an even pressure distribution between the backplate inner surface 18 and the shroud inner surface 24. Thus, any one of the three vane systems of Figs. 1, 3, or 4, may be used initially, and changed in their adjustment to secure the desired degree of pressure distribution.

The use of backwardly sloped impeller vanes 20 endows the impeller itself with some diffusing action—that is, that air delivered at the impeller periphery will have a lower velocity head and a higher pressure head than is obtainable with impellers having radial, rather than retreating spiral, vanes. The use of the integral impeller shroud 23 makes the spiral form vanes 20 possible whereas, when the blades are supported only by the backplate, they must necessarily have radial form in order to be adequately supported against centrifugal force.

The flattened spokes 31, 35 and 41 for the sev-

eral types of turning vanes have the functions not only of supporting the turning vanes but also of acting as axial flow guides tending to prevent rotation of the air mass entering the impeller eye before same has been attacked by the leading edges of the impeller vanes.

While I have described my invention in detail in its present preferred embodiment, it will be obvious to those skilled in the art, after understanding my invention, that various changes and modifications may be made therein without departing from the spirit or scope thereof. I aim in the appended claims to cover all such modifications and changes.

I claim as my invention:

1. In a blower assembly, an impeller comprising a hub element secured to a shaft, the element having a concave surface of revolution, the outer part of said surface blending into a plane surface, integral blower vanes extending therefrom in an axial direction, the inner leading edges of said vanes lying substantially at the junction of the curved surface and plane surface and extending to the impeller periphery, a shroud element radially substantially coextensive with said blower vanes at their other ends, the zone inward of the vane leading edges comprising the impeller eye, and a plurality of stationary annular guide vanes in said eye, said guide vanes being curved in cross section in substantial complement to the curvature of said

surface of revolution and being staggered successively closer to the impeller axis and disposed more remotely from the leading edges of said blower vanes.

5 2. In a centrifugal blower, a shrouded impeller having a backplate and circumferentially spaced vanes between the backplate and the shroud, the shroud having a thickened and rounded inner edge defining an axial air entrance opening, a first narrow annular turning vane in the air entrance opening having its leading edge tangent to the entering airstream, and having its trailing edge tangent to a radius and spaced from the inner wall of the shroud a smaller distance than the leading edge is spaced, and a second annular turning vane, of substantially the same cross section as the first, having both its leading and trailing edges disposed upstream of the leading and trailing edges respectively of the first vane, the chord of the first vane being sloped at a greater angle to the impeller axis than the chord of the second vane whereby the air passing from between said vanes influences the airflow leaving the other passages defined in the impeller eye, all of said vanes being spaced more closely to the shroud inner edge than to the impeller backplate, whereby a clear air passage of substantial width, unencumbered by vanes, is defined between the impeller backplate and the innermost turning vane.

KENNETH CAMPBELL.
